WHIPSTOCK ANCHOR.

Filed July 1, 1929

Fig. 1.

UNITED STATES PATENT OFFICE

BARTHOL B. LUND, OF LONG BEACH, CALIFORNIA

WHIPSTOCK ANCHOR

Application filed July 1, 1929. Serial No. 375,274.

This invention relates to a whip stock anchor by means of which the whip stock is securely fastened in the hole so that it will not move prior to or after the time that the bit is again inserted into the hole for the purpose of drilling in the proper direction.

It will be understood that in the rotary drilling of wells, and particularly oil wells, the bit is deflected from the vertical to a very considerable extent. This condition is very undesirable because of the bends in the casting, tube, sucker rods and the like.

Whip stocks have been used heretofore and their purpose is to deflect the bit from its angular direction to the proper vertical direction or as nearly the vertical as possible. Heretofore the whip stock has been cemented in place which requires considerable time in that the cement had to set, and also it was frequently found that the whip stock floated away from the position that it should properly take, and was found a considerable distance upwardly in the well.

An object of my invention is to provide a means whereby a whip stock may be positively anchored in the well, and may be held in proper position without use of cement or any other similar material.

Other objects, advantages and features of the invention may appear from the accompanying detailed description on the appended claims.

In the drawing

Figure 1 is a side elevation of my whip stock in position in a well, the well being shown in section.

Figure 2 is a longitudinal section view of the whip stock.

Figure 3 is a section view taken on the line 3—3 of Figure 2.

Referring more particularly to the drawing, the numeral 1 indicates the well bore which frequently extends off at an angle from the vertical, as shown at 2. It is the angular direction of the bore which must be rectified.

The whipstock 3 is placed in the angular part of the bore 2, and the tapering upper edge 4 of the whip stock is so set that when the bit strikes this said tapering edge surface it will be deflected into the proper vertical di-

rection. I have here shown the whip stock as resting on the bottom of the hole, however, it will be evident that the hole may be cemented at a certain point, and the whip stock shall not move once it is set in position, and 55 also that the upper edge 4 shall not turn otherwise the bit would be deflected in the wrong direction.

My whip stock includes an upwardly tubular section 5 the top of which is formed 60 with the inclined edge 4.

A sleeve 6 is slidably mounted in the tube 5 and projects from the bottom thereof. A plug 7 may be screwed into the bottom of the sleeve 6 to close the same, and also to 65 enable the sleeve to readily pass under the angular positions of the hole.

A pair of dogs 8—9 are pivotally mounted in the sleeve 6 upon a pin 10, which pin is suitably secured or journaled in the sleeve. 70 The dogs 8—9 project through slots 11—12 respectively in the sleeve 6, and through co-incident slots 13—14 respectively in the tube 5. It will be evident that when the sleeve 6 moves upwardly in the tube 5, that 75 the dogs 8—9 will be swung outwardly, and projected into the formation. Once this is accomplished, the whip stock is securely held, and can neither rotate nor move upwardly in the hole. 80

A stop pin 15 is provided in the tube 5 for the purpose of limiting the upward movement of the sleeve 6. The whip stock 3 is lowered into the hole on the bottom of usual pipe or tube 16, and the whip stock is held on the pipe by small rivets or bolts 17. When the bottom is reached the weight of the pipe causes the tube 5 to slide downwardly over the sleeve 6 through forcing the dogs 8—9 outwardly into the formation. A further lowering of the pipe will cause the bolts 17 to shear off so that the whip stock can remain in the hole. 85

Having described my invention I claim:

1. A whipstock including an upper tubular section, a lower sleeve section slidable in said tube, and protruding therefrom, said tube and sleeve having co-incident slots formed therein, a pair of dogs pivotally mounted in 100

said sleeve, said dogs being adapted to protrude through said slots.

5 2. A whip stock including an upper tubular section, a lower sleeve section slidable in said tube, and protruding therefrom, said tube and sleeve having co-incidental slots formed therein, a pair of dogs pivotally mounted in said sleeve, said dogs being adapted to protrude through said slots, a plug in the bottom of said sleeve, and a stop pin in said tube adapted to limit the upward movement of said sleeve.

10 3. A whip stock including a tubular section, an upper inclined edge on said tube, a sleeve slidable in the tube and protruding from the bottom thereof, a plug screwed into the bottom of said sleeve, a stop pin in the tube adapted to limit the upward movement of the sleeve, said tube and sleeve having oppositely positioned co-incidental slots formed therein, a pair of dogs protrudingly secured in the sleeve and protruding through said slots, said dogs being adapted to be swung outwardly when the sleeve moves upwardly.

15 20 25 In testimony whereof, I affix my signature.
BARTHOL B. LUND.
